SAM EVERETT FINLEY, OF ATLANTA, GEORGIA.

METHOD OF TREATING ROADWAYS.

1,341,458.

Specification of Letters Patent. Patented May 25, 1920.

Application filed October 29, 1919. Serial No. 334,316.

To all whom it may concern:

Be it known that I, SAM E. FINLEY, residing at Atlanta, county of Fulton, State of Georgia, have invented certain new and 5 useful Improvements in Methods of Treating Roadways; and I do hereby declare the following to be a full, clear, and exact description of the invention, such as will enable others skilled in the art to which it 10 appertains to make and use the same.

The invention relates to the application of binding media to road beds having a surface of broken stone, gravel and similar material, which before treatment is liable 15 to be rutted and displaced by the wheels of a vehicle traversing the same, and to this end the new method comprises the application of the broken stone, or the like, to the roadway, working the same to the desired 20 cross section and surface contour, uniformly coating one longitudinal section of the road surface with a binding medium by lateral application of said medium from a spraying machine traversing an adjacent 25 section, restoring the surface of the latter section, which has been marred by the passage of the spraying machine thereover, and subsequently applying a similar uniform coating of the binder to the restored 30 surface of the latter section by the machine traversing the previously treated and finished section, or an adjacent untreated section.

Suitable mechanism for carrying out the 35 method aforesaid is illustrated in the accompanying drawing, in which the single figure represents a spraying machine having a laterally disposed header device applying the binding medium to one longitudinal section of a roadway while the wheels 40 of the vehicle are traversing an adjacent untreated section of the roadway.

While the invention is applicable to the 45 treating of roadways generally, with oils, tars and the like, it affords a particularly efficacious mode of application of heavy bituminous or asphaltic materials to a broken stone or gravel surfaced roadway to produce what is known as an asphalt 50 macadam surface; the binding medium penetrating the voids or interstices between the solid material of the road bed and serving to bind the same into a homogeneous, resilient, wear resisting way for traffic, which 55 becomes immediately available for use after the coated surface has been finished

with a top dressing of fine stone screenings, sand, or the like, with or without a second or seal coat of oil or other suitable medium and a final top dressing of screenings or 60 sand. It is found that the best results in constructing permanent roadways with bituminous, asphaltic, and similar materials, are obtained when the binding materials are of such consistency and stability as to 65 require heating to relatively high temperatures to reduce them to the necessary condition of fluidity for application to the broken stone or gravel on the road surfaces by means of a spraying or jetting machine employing what is commonly termed "the penetration method" in which the 70 treating medium is caused to penetrate the solid material of the road surface to a considerable depth and thereby effecting a 75 thorough cementation or union between such solid material and the binder, so that the road surface will effectively resist any tendency to rut or scour off and will be 80 highly resistant to the attrition of traffic and the disruptive effects of climatic conditions.

Heretofore it has been the general practice to distribute the binding medium on to a road surface by means of a horse drawn 85 or power driven vehicle provided with a spraying manifold or distributor located at the rear of the machine so that the weight of the vehicle frequently caused the road surface, consisting of loose or slightly 90 compacted broken stone, or gravel, to rut and to be otherwise marred or displaced, which necessitated the surface to be again brought to grade by suitable working after the binding material had been applied 95 thereto, as otherwise the liquid binding medium would collect in the ruts and depressions from which it would be subsequently picked up by the wheels of traffic, or would tend to exude or bleed through 100 the surface during the hot summer weather and, what is an even more serious condition, the collecting of the binding medium in pools or pockets would prevent the even distribution of such material throughout 105 the road surface and would leave certain portions of the road surface with little or no binding material thereon, so that such unbound sections of the road would scour out and require re-treatment in very short 110 time. To remedy these conditions it was necessary to immediately re-distribute the

collected pools of oil, or the like, by hand brooming, or other methods, and to work out the depressions and irregularities in the road surface whenever relatively light 5 treating binding media were employed, but even this method of correcting the difficulties is more or less unsatisfactory and highly expensive. In the treatment of roads with the relatively heavy materials 10 of great stability even this corrective method is inapplicable because when once the binding medium is deposited on the road the treated surface cannot be successfully re-worked and brought back to proper 15 grade by eliminating the ruts and depressions formed by the wheels of the spraying machine or the hoofs of the horses, as it is impossible to roll out the ruts or depressions in the road surface produced during 20 the application of the binding medium and after the same has lost the applied heat necessary to bring it to a state of fluidity. The effect of such ruts and depressions in the finished road surface is to permit water 25 to collect and stand which immediately sets up a disintegrating action and also causes an uneven and unsatisfactory surface for traffic which would, moreover, cause the vehicle wheels to further break up or disrupt 30 the surface as they ran over the edges of the ruts or depressions.

The present invention is designed to completely overcome these various difficulties and objections and permit the successful application of various grades of binding 35 media, from the lighter treating oils to the heavier and highly stable asphalts and bitumens, without the necessity of re-working the treated roadway, so that the latter, after 40 the application of the binding medium, is left as a smooth thoroughly bonded surface of proper cross section and surface contour.

Referring to the accompanying drawing, the machine illustrated therein is of a type 45 described and claimed in my co-pending application filed of even date herewith and involves a motor propelled wheeled vehicle having thereon a tank 10 in which the road treating material is stored under a uniform 50 pressure of air delivered by an air compressor to a series of air storage tanks, of which two 50 and 51 are shown, said tanks being appropriately connected to the dome of the tank by a valved pipe, which is provided with a pressure regulator to insure 55 uniformity of the air pressure in the tank, and a check valve interposed between the material tank and the pressure regulator to prevent back flow of gases or liquid to the 60 pressure regulator.

Disposed at the rear of the vehicle and movable transversely thereof in yokes 25 is a carrier 26, in which is fixed a supply pipe 21 which is connected at its middle portion 65 with an outlet pipe from the bottom of the

tank 10 by means of a vertical pipe 19 having a valve 20 therein.

The means for laterally adjusting the carrier 26 consists of a rack section 27 disposed at the middle of said carrier, which is engaged by a pinion 28 on the lower end of a hand wheel shaft 29, which latter is rotatably mounted in the standard or casing 30 mounted upon a bridge piece 31 connecting the yokes 25, which are slidably mounted for 75 longitudinal movement on rearwardly extending angle pieces 1¹, 1¹ attached to the rear of the longitudinal sills of the chassis. The supply pipe 21 is provided with cutoff valves 24 and 24¹ disposed on each side of 80 the connection of said pipe with the pipe from the tank 10 so that the binding material from the tank may be delivered to either or both sections of said pipe 21 by opening or closing the appropriate valves 24 and 24¹. 85 Each end of the supply pipe 21 is provided with a T coupling 22, the outer end of which is suitably stopped with a screw plug and the vertical member has a short section of pipe 23 secured thereto. 90

In the old type of machines heretofore employed, the distributor header or manifold would ordinarily have been secured to the pendant pipe sections 23, 23, so that the header would be disposed below and parallel with the supply pipe 21, and, therefore, transversely of the rear of the vehicle, so that the oil would be distributed by the manifold directly over the path traversed by the wheels of the vehicle, and, therefore, 100 cause the distributed oil to collect in the ruts or depressions formed by the wheels of the vehicle, to the detriment of the road surface as hereinbefore explained. 95

In the adaptation of the distributing machine to the application of the method constituting the present invention, instead of disposing the distributor header or manifold transversely of the rear of the machine it is located wholly to one side of the machine 105 and, therefore, out of the line of travel of the wheels of the latter. This is effected, as illustrated in the drawings, by uncoupling the left hand end of the distributor header or manifold from the corresponding end of the 110 supply pipe 21 and swinging the manifold or header through an angle of 180 degrees on either the T coupling 22 or on the intermediate coupling 43 and then applying an auxiliary pipe section 90 to the right hand 115 T coupling 22 on supply pipe 21 and engaging a short vertical pipe section 92 on the end of auxiliary pipe 90 with the detachable coupling 44 on the upper end of pipe section 42, which latter is connected to 120 the manifold or distributor. The extreme outer end of the header or distributor system is supported by a suitable brace or stay rod 93, attached at one end to T coupling 91 on the end of auxiliary pipe 90, and 125 130

at the other to a suitable bracket or standard 35 which is secured to the carrier 26, so that the entire header or distributor manifold is rigidly supported by the carrier 26 and is laterally adjustable transversely of the roadway to the full extent of lateral movement of said carrier, thereby permitting the header to be moved laterally to avoid obstacles or irregularities in the contour of the road and to prevent over-laps in the road treating material, as well as to avoid untreated spaces of the road surface, as fully set forth in the co-pending application aforesaid. The distributor header or 15 manifold preferably consists of two parallel pipe sections having spray nozzles disposed longitudinally thereof in staggered relation on the two pipes so that the conical sprays delivered in a vertical direction will apply 20 the binding material to the road surface in an even uniform layer. It will be particularly noted that the entire distributor system, or at least the jetting manifold or distributor header or pipe, is disposed entirely outside 25 of the line of travel of the adjacent wheels of the vehicle and that none of the road material falls upon the road surface over which the wheels have passed, but all 30 of the binding material is delivered to the surface of the road wholly lateral of and extraneous to the wheel tracks.

According to the present invention, the roadway is provided with a covering of broken stone, gravel, or other suitable road building solid material, which is worked to approximate surface contour and cross section and then rolled to the ultimate surface desired by suitable road roller. Preferably the whole road surface is thus treated, but, 40 if desired, only that portion of the road surface which is to subsequently receive a coating of the binding medium may be worked up to proper surface conditions. When this has been effected the machine with the heated road binding medium therein is brought on to the road laterally of the particular longitudinal stretch or section of the road to which application of the binding medium is to be made. As graphically 45 illustrated in the drawing, the wheels of the vehicle, which is usually very heavy, form depressions, tracks, or ruts in the relatively loose ballasting on the road, but the binding medium is delivered to the uniform, unmarred, previously rolled surface of the lateral section of the road, above which the laterally disposed jetting manifold or header travels, so that the binding medium is applied uniformly to the perfectly prepared 50 surface of the broken stone, gravel, or the like, and is evenly distributed over and throughout the material under ideal conditions to produce a uniformly bound road surface without ruts, depressions or other 55 irregularities therein. It will be further

noted that the course of distribution of the binder may be varied, wherever it be found necessary, by adjusting the header or distributor manifold laterally of the line of travel by means of the hand wheel shaft 29 and the rack and pinion connection 27 and 28 between said shaft and the carrier 26, which latter supports the header apparatus. After the prescribed section of roadway has been covered with a uniform coating of the binding material it is finished by applying thereto a layer of stone chips, screenings, sand, or the like, which serves to absorb the binding material remaining on the surface of the roadway and also to provide the necessary wearing surface and prevent the binding media picking up or adhering to the wheels of traffic or the feet of pedestrians, or, if a second or seal coat of binding medium is desired, the same may be applied 85 in any suitable manner, either before or after the fine stone or sand has been spread over the first coat, and said seal coat is then covered with stone screenings, sand, or the like. This final surface dressing also brings 90 the road at once to a condition for use by traffic without danger of rutting or marring the surface. When the machine reaches the end of the section to be treated, and the latter has received its surface dressing, as 95 hereinbefore explained, the vehicle is run upon the section of the road previously treated, or as the case may be, upon another untreated section, so that the manifold or spray header lies over the section of the 10 road which has just been traversed and rutted up by the wheels of the vehicle. Previous to the application of the binding medium to this rutted section of the road surface, however, the latter has been again re-worked with the road roller, or other suitable means, to take out the wheel ruts and any other irregularities which may have been produced in the surface formed by the broken stone, or the like, so that the previously marred section is again brought to proper grade and surface contour. The machine is then driven along the previously treated road section Y and the binding medium sprayed evenly over the adjacent lateral section X, which had been marred by the wheels of the vehicle and subsequently restored by the road roller, or other suitable apparatus. As the vehicle progresses the material is distributed in an even and uniform layer over the road section X and, by reason of the facility with which the manifold or header may be adjusted, the meeting edges of the previously treated section Y and section X under treatment may be accurately matched without any over-lapping of the sheets of applied material, so that no excess of the treating material will be applied to any portion of the road. This is readily effected by an operator who stands 120

on the rear of the machine at the hand wheel shaft 29 and observes the transverse areas of dispersion of the treating material delivered from the header or manifold, and by 5 manipulating the hand wheel adjusts the carrier 26 and the header apparatus transversely of path of travel to cause the adjacent edges of the layers of road treating material to meet but not to over-lap. Similarly, the header may be adjusted to avoid 10 obstacles and to reach previously untreated sections of the road, lying within the range of adjustment of the header. After the section X of the road has received the proper 15 application of binding medium it, in turn, is provided with a coating of stone screenings, sand, or the like, and, if necessary, a seal coat of binding medium with a top dressing of screenings or sand, when it is 20 immediately ready for traffic.

In roads of ordinary width it will be possible to treat the entire surface by traversing the machine longitudinally, first over one-half of the road in one direction, and 25 then over the other half of the road in the opposite direction. If the roadway is too wide to admit of this mode of operation the vehicle will be operated over successive longitudinal sections of a road in order, the 30 second and subsequent applications being effected by the vehicle proper being driven over the previously treated and finished section of the road.

It has been found that the method as 35 hereinbefore described materially reduces the cost of treating the roadway by a saving of time and material, whatever the character of the binding medium employed may be, and renders the treatment of roadways 40 with heavy or highly stable binding media in an economical manner feasible for the first time and renders it possible to produce an absolutely uniform road surface without the necessity of re-working the same after it 45 has been treated to attempt to eliminate defects which were produced by the machine making the application of the binding medium thereto.

What I claim is:

50 1. The method of treating roadways which comprises applying a uniform coating of binding material to one longitudinal section thereof by means of a traveling vehicle traversing an adjacent section, ap-

plying a top dressing to the coated section, 55 restoring the surface of the traversed section where the same has been marred by the vehicle or otherwise, and applying a similar coating of binding material to the restored section by said vehicle traversing the previously treated section. 60

2. The method of treating roadways which comprises building up a surface of broken stone, or the like, working the same to the desired cross section and surface 65 contour, uniformly coating one longitudinal section with a binding medium by lateral application from a traveling vehicle traversing an adjacent section, applying a top dressing to the coated section, restoring the 70 surface of the traversed section, and applying a uniform coating of the binder to the restored surface by the vehicle traversing the previously treated section.

3. The method of treating roadways 75 which comprises building up a surface of broken stone, or the like, working the same to the desired cross section and surface contour, traversing a binder distributing vehicle having a laterally disposed spray header 80 over one longitudinal section of the road surface and simultaneously applying a coating of binding material to an adjacent longitudinal section, covering the coated section with stone chips, sand, or the like, 85 re-working the first section marred by the vehicle to restore the cross section and surface contour thereof, and applying a coating of binding medium to the restored section by the distributor vehicle traversing 90 the previously treated section or a laterally adjacent untreated section.

4. The method of treating roadways 95 which comprises applying a coating of binding material to one longitudinal section thereof by means of a traveling vehicle traversing an adjacent section, restoring the surface of the traversed section where the same has been marred by the vehicle or otherwise, and applying a similar coating 100 of binding material to the restored section by said vehicle traversing the previously treated section after the latter is in condition for traffic.
